UNITED STATES PATENT OFFICE

2,470,423

ELECTRICAL SPlicer

William H. Alford, Winston-Salem, N. C.

Application December 29, 1945, Serial No. 637,931

2 Claims. (Cl. 174—84)

1

My invention relates to wire splicing devices with particular reference to one which is adapted for connecting the ends of insulated wires, one of the primary objects of the invention being to effect connection of wire ends without necessitating the removal of their insulation covering.

The device is particularly adapted for use where a temporary connection of wires is to be made as for instance, when it is desired to lengthen the power cord of a radio set or fixture, the splicing or connection being effected without requiring any tools and in a very short time, no skill on the part of the operator being required.

The invention also contemplates a device for the purpose stated, which is very simple in construction, strong and durable, inexpensive to manufacture and entirely safe and very efficient in practical use.

The invention resides in certain novel features of construction, combination and arrangement of parts to be hereinafter described and claimed, reference being had to the accompanying drawing which illustrates the now preferred form.

It is to be understood, however, that the disclosure is to be taken merely as illustrative, it being obvious that various changes and modifications may be made therein without departing from the spirit and scope of the invention as hereinafter claimed.

In the drawings, wherein the same reference characters have been used to designate the same parts throughout the several views,

Fig. 1 is a central longitudinal sectional view of a wire splicer or connector embodying my invention;

Fig. 2 is a cross-sectional view through one of the end sleeves showing the opposed opened jaws having the insulation piercing pins and apertured guard plates;

Fig. 3 is a lineal sectional view through one of the jaws and associated guard plate in pin-shielding position;

Fig. 4 is a view similar to Fig. 3, but showing the guard plate flattened out and the jaw pins projected through the apertures thereof to pierce the insulation covering of a wire; and

Fig. 5 is a plan view, partly in section, of one of the wire guiding and pin guarding plates.

Referring specifically to the drawings, numeral 6 designates a pair of duplicate sleeves of insulating material, a phenol condensation product, for instance one commercially known as Bakelite being especially suitable.

Each sleeve 6 has a medial lineally extending wire end receiving bore opening from its outer

2

end and communicating with an outwardly flared cam providing portion 8. This flared cam providing portion 8 of the bore 7 terminates short of the enlarged threaded inner end 9 of said bore.

By preference the bore 9 of the left hand sleeve 6, as viewed in Fig. 1, will have left hand threads, while the threaded bore portion 8 of the right hand sleeve will have right hand threads. The inner ends of the sleeves 6 are threaded onto an exteriorly threaded cylindrical connector 10 having left hand threads 10a leading from one end and right hand threads 10b leading from the other end, there being a thread stop or shoulder 10c to separate the threads 10a, 10b.

The sleeve connector 10 will, of course, be of insulating material and has the central lineally extending bore 11 receiving in the present instance, a pair of stiff spring metal conductor strips 12 having their outer ends extending beyond the outer ends of the bore 11 and bent laterally in opposite directions as indicated at 12a. To the outer end of each of the spring metal conductor strip portions 12a is welded or otherwise secured a transversely arcuate jaw plate 13 of spring metal.

As illustrated, the two jaw plates 13 within each sleeve 6 are arranged in opposition to one another and have the sharp pointed inwardly extending insulation piercing pins 14.

In order to admit of insertion of the wire ends between the jaw plates 13 without snagging on the pins 14, I provide guide plates 15 which are secured to the jaw plates at their outer ends only, and overlie the points of the pins 14. The wire guiding plates 15 are preferably of very light spring metal and they are arcuate in cross section to conform to the transverse curvature of jaw plates 13. Guide plates 15 have apertures 16 arranged in opposition to the pins 14 so as to allow the pins to project through the insulation covering of the wire when the opposed jaw plates are drawn together.

It will be apparent that when the insulated ends of wires 17 have been inserted into the bores 7 and disposed between the guide plates 15, electrical connection of said ends can be effected by simply screwing up the sleeves 6 to cause the rounded ends of the jaw plates 13 to ride up the cam portions 8 of bores 7. This causes the pins 14 to be projected through the holes 16 of the guide plates 15, it being understood that the free ends 15a simply slide along the conductor strip portions 12a as said plates yield under pressure. The responsive give to the pres-

sure exerted is at the jaw carried ends 15b of the guide plates 15, as will be evident.

When it is desired to release the splice or connection of the wire ends 17, it is only necessary to back the sleeves off the connector 10. Due to the spring action of the conductor strip ends 12a, the jaws 13 separate. The wire guide plates 15 being of spring material also assist in stripping the hold of the insulation covering of the wires from the pins 14.

From the foregoing description, taken in connection with the drawing, it will be apparent that a very simple and effective wire splicer has been provided. The metal conductor 12, while mentioned as being in separate parts may, of course, be made of one piece with split ends 12a. Many other modifications in the structure illustrated will also suggest themselves.

Having thus described my invention, what I claim is:

1. An electrical wire splicer comprising in combination a pair of sleeve members, each of said members having a lineally extending wire end-receiving bore opening from its outer end, an enlarged threaded connector receiving bore opening from its inner end and a flared cam-providing bore portion connecting said aforementioned bores, the entire length of the thus provided opening through each sleeve being at least insulation-surfaced, an exteriorly threaded connector having its ends operatively engaged in the respective threaded bores of said sleeve members, said connector having a conductor receiving passage extending therethrough and communicating with said enlarged threaded sleeve bores, electrical conductor means extending through said connector passage, opposed oppositely directed spring material arms at each end of said conductor means, a pair of opposed wire terminal-engageable jaws in the threaded bore portion of each sleeve and carried by the respective adjacent spring material conductor-carried arms, the outer ends of the jaws normally bearing against the sleeve bore inwardly of the outwardly flared cam portion thereof, and insulation piercing means projecting inwardly from each of said jaws.

2. An electrical wire splicer comprising in combination a pair of sleeve members, each of said members having a lineally extending wire end-receiving bore opening from its outer end, an en-

larged threaded connector receiving bore opening from its inner end and a flared cam-providing bore portion connecting said aforementioned bores, the entire length of the thus provided opening through each sleeve being at least insulation-surfaced, an exteriorly threaded connector having its ends operatively engaged in the respective threaded bores of said sleeve members, said connector having a conductor receiving passage extending therethrough and communicating with said enlarged threaded sleeve bores, electrical conductor means extending through said connector passage, opposed oppositely directed spring material arms at each end of said conductor means, a pair of opposed wire terminal-engageable jaws in the threaded bore portion of each sleeve and carried by the respective adjacent spring material conductor-carried arms, the outer ends of the jaws normally bearing against the sleeve bore inwardly of the outwardly flared cam portion thereof, and insulation piercing means projecting inwardly from each of said jaws, a wire end-guiding shield overlying the insulation-piercing means of each jaw and having an aperture opposite each of said piercing means, and a spring like connection between each of said shields and its associated jaw at the outer end only of same.
